NERVE TESTING MACHINE

George P. Mahoney, Baltimore, Md.

Application January 5, 1942, Serial No. 425,703

1 Claim. (Cl. 171—119)

My invention relates to nerve detection, and has among its objects and advantages the provision of an improved electrical instrument for detecting impairment of nerves in the legs of race horses and the like.

The unnerving of race horses has frequently been practiced by unscrupulous trainers. Often when a racer gives way to soreness in a weak leg, the conditioners employ the services of a veterinarian to kill the nerves above the weak joint of the leg. After the nerves have been cut, the racer performs on a leg which is dead. Frequently an unnerfed leg will give way during the running of a race. It often happens that the hoof of the horse rots off as a result of having been unnerfed. Unnerfing has been the cause of many broken legs. Heretofore there has been no way of definitely detecting when a racer has been unnerfed.

Accordingly, an object of my invention to provide a novel instrument designed to pass an electric current through the main nerves in the legs of the animal to determine whether the nerves have been impaired. If the nerves have been destroyed, there is no reaction on the part of the animal to the current. However, animals which have not been unnerfed will indicate that fact through shifting of their legs and observable muscular movement.

In the accompanying drawings:

Figure 1 is a face view of an instrument in accordance with my invention;

Figure 2 is a view taken substantially along the line 2—2 of Figure 1;

Figure 3 is a side view with the wall removed;

Figure 4 is a sectional detail view of a transformer and resistance incorporated in a housing;

Figure 5 is a perspective view of an attaching clip for holding the contacts or electrodes against the leg of the animal; and

Figure 6 is a diagrammatic view of the electric circuit.

In the embodiment selected for illustration, I make use of a housing or cabinet 10 which is of small proportions to facilitate handling and carrying from place to place. The front face 12 of the cabinet is provided with an opening 14 closed by a face plate 16 provided with a circular opening 18 in which is snugly fitted one end of a housing 20 secured to a mount 22 attached to the rear wall 24, as by screws 26. Inside the housing 20 is arranged a transformer 28 attached to the mount 22. A fixed resistance 30 is also secured to the mount 22 while a second resistance 32 is

mounted on a U-shaped bracket 34 attached to the mount 22 by screws 36.

Rotatably journaled in the bracket 34 is a screw 38 threadedly connected with a contact 40 5 slidingly engaging the resistance 32. The resistance 32 parallels the bight 42 of the bracket 34 and the contact 40 is slidably mounted on the bight. To the contact 40 is connected a pointer 44 which extends through a slot 46 in the end wall 48 of the housing 20. To the end wall 48 is 10 attached a voltage indicating scale 50 along which the pointer 44 slides to indicate service voltage being utilized, as when the contact 40 is adjusted along the resistance 32. The pointer 44 moves 15 as a unit with the contact 40 when the latter is adjusted along the resistance 32 through rotation of the screw 38.

The screw 38 is restrained from longitudinal movement and is provided with a square end 52 20 for connection with a socket 54 at one end of a tool 56 insertable through an opening 58 in the side wall 60. A knurled knob 62 is attached to one end of the tool 56 to facilitate rotation thereof, and the housing 20 is provided with an opening 64 through which the square end 52 extends and into which the socket 54 is receivable for connection with the square end.

In Figure 6, the resistance 30 is connected with a wire 64 attached to a plug 66 which may be 30 plugged into an ordinary wall outlet. The second wire 68 attached to the plug 66 is lugged to a wire 70 leading to a dial lamp 72 located above the scale 50, as in Figure 1. The second wire 74 connected with the dial lamp 72 leads to a terminal 76 of a service switch 78 mounted on the wall 48 of a housing 20. The wire 70 leads to a terminal 80 of a switch 82 also mounted on the wall 48. The switch element 84 of the switch 82 is connected with a wire 86 lugged to the wire 74.

To the other end of the resistance 30 is connected a wire 88 connected with the resistance 32 engaged by the contact 40. The bight 42 is 45 connected with a wire 88 connected with the primary winding 90 of the transformer 28, this winding connecting with a wire 92 to which a wire 94 connected with the resistance 32 is lugged. Wire 92 connects with the switch element 96 of the switch 78. Wire 88 leads to a terminal 98 of a socket 100 mounted on the wall 48, this socket being provided with a second terminal 102 connected with a wire 104 lugged to the wire 92. The cord 106 of an extension lamp 108 may be 50 plugged into the socket 100.

One end of the secondary winding 110 of the 55 transformer 28 connects with a wire 112 leading

to a terminal 114 in a connector 116. The other end of the winding 110 is connected with a wire 118 leading to the second terminal 120 of the connector 116. The wires 122 and 124 of a cord 126 are respectively connectable with the terminals 114 and 120 through the medium of a companion connector plug 128, see Figure 1. Electrodes or contacts 130 and 132 are respectively connected with the wires 122 and 124. These electrodes are mounted in a head 134 at one end of a handle 136 on the cord 126 to facilitate manipulation thereof. A similar handle 138 is provided on the cord 106 to facilitate handling of the extension lamp 108.

A neon lamp 140 is mounted on the face plate 16 and is electrically connected with the wires 112 and 118 through the medium of leads 142 and 144, respectively. An indicator lamp 146 is mounted on the face plate 16 and electrically connected with the wires 64 and 68 to indicate whether the plug 66 is making contact with the outside circuit.

In operation, the electrodes 130 and 132 are applied to the leg region under examination. The voltage may be regulated through adjustment of the screw 38. When the connectors 116 and 128 are coupled, the electrodes 130 and 132 are electrically connected with the secondary winding 110. The neon lamp 140 is also electrically connected with the secondary winding. The closing of the switch 78 energizes the circuit. When making examination in the dark, the lamp 108 is plugged into the socket 100. With the switch 82 open, the dial lamp 72 is energized, and closing of the switch deenergizes the dial lamp in that the current is by-passed through the terminal 80.

The unit is compact, light in weight and easily carried from place to place. I have found that an instrument of this type is highly effective in determining the nerve conditions of the animal.

Figure 5 illustrates a modified electrode unit wherein the head 148 corresponding to the head 134 is provided with a spring clip 150 which em-

braces the leg of the animal for holding the electrodes 152 thereagainst.

Without further elaboration, the foregoing will so fully illustrate my invention, that others may, by applying current knowledge, readily adapt the same for use under various conditions of service.

I claim:

In testing apparatus of the character described, a rectangular cabinet having a rear wall and a front wall and an opening in its front wall, a supporting mount secured to the inner side of the rear wall of the cabinet, a cylindrical housing connected to and extending forwardly from said mount and provided with a horizontally extending graduated slot in its front wall, the front wall of the housing fitting into the opening in the front wall of the cabinet, a U-shaped bracket fastened to and extending forwardly of said mount within the housing to a point adjacent the front wall, a resistance element supported in transverse position on the bracket, a screw rotatably mounted on the bracket adjacent the slot in the front wall, a contact element operatively related with said resistance element and mounted for transverse movement by said screw, a pointer connected to said contact element and extending through said graduated slot, a selectively operated switch mounted on the front wall of the housing, a transformer and a fixed resistance element connected in circuit with said first resistance and switch within the housing, an extension stem extending through registering openings in the side walls of the cabinet and housing and detachably engageable with the screw for manual turning of the screw from a position exteriorly of the cabinet, and a plurality of conductors connected with the circuit in the housing and extending exteriorly of the housing and cabinet for connection with a source of electric current and with contact electrodes respectively.

GEORGE P. MAHONEY.
